UNITED STATES PATENT OFFICE.

JAMES HESELWOOD, OF LEEDS, ENGLAND.

MACHINE FOR FOLDING CURTAINS.

SPECIFICATION forming part of Letters Patent No. 606,341, dated June 28, 1898.

Application filed August 26, 1897. Serial No. 649,582. (No model.)

To all whom it may concern:

Be it known that I, JAMES HESELWOOD, a subject of the Queen of Great Britain and Ireland, and a resident of Leeds, in the county 5 of York, England, have invented certain new and useful Improvements in Machines for Folding Curtains, of which the following is a specification.

The object of this invention is to construct 10 machinery whereby curtains may be straightened out and folded after washing while in a damp condition, and the said curtains may be thus dried without danger of tearing or crinkling the fabric.

15 In order that my invention may be clearly understood, I will proceed to describe same with reference to the accompanying drawings, in which similar letters and numerals refer to like parts in all the figures.

20 Figure 1 is a side elevation of a machine constructed according to my invention, and Fig. 2 is an end view of same. Figs. 3, 4, 5, and 6 are diagram views illustrating the working of the machine.

25 According to my invention I provide a table A, which is of sufficient length to carry a curtain stretched longitudinally on same, and at the ends of the table A two uprights B and C are provided, being carried on the frame D 30 of the machine.

35 E is a shaft carrying two pulleys F and G, over which chains H pass for the support of two carriers J J, which are connected together by a carrier-rod K, having pins K' on its under side.

40 L are counterbalance-weights which are attached to the opposite ends of the chains H, and M is a rod which is carried on hooks N N, attached to the carriers J J. On the framework D at each end of the machine two shafts P P' are mounted, the shaft P being provided with spur-gearing R, through which it is connected with left and right driving-pulleys S S'. The shafts P P' are formed 45 with right-handed screw-threads on one side of their bearings and with left-handed screw-threads on the other side of their bearings, and the two shafts are connected together by means of chain-gearing T. Above the table 50 A two movable narrow tables U and V are provided, being carried on the screw-shafts

P P' and on slides W W', fixed to the end-frames of the machine, in such a manner that the rotation of the shafts P P' causes the narrow tables U and V to slide on the rods W 55 W' and to move toward or away from the center of the table A, according to the direction of rotation of the shafts P P'.

Z is a belt-fork which is carried on a sliding rod 2, and adjustable tappets 3 are provided on the said rod for the purpose of engaging with the narrow tables U and V as they come to the limit of the movement required, thus causing the sliding rod 2 to be moved and the machine to be reversed or 65 thrown out of gear.

4 is a pulley which is attached to the shaft E, and 5 is a chain which enables the said shaft E to be rotated by hand and thus to raise or lower the carriers J J at will. 70

6 is an open frame, on which the curtain is folded by the machine for drying purposes.

The curtain is folded down the center on a suitable table provided for the purpose, and the loose rod M is inserted in the fold, so as 75 to divide the curtain equally on both sides. The rod M is then lifted up and placed in the hooks N on the carrier K, and the sides of the curtain are drawn over the narrow tables U and V, as shown in the diagram at Fig. 3. 80 On the narrow tables U and V being moved apart through the medium of the screw-shafts P P' the carrier K, with its rod M, is lowered, the pins P' keeping the curtain central as the tables separate until the narrow 85 tables U and V reach the limit of their action, as seen at Fig. 4. The rod M is then withdrawn from the carrier and the latter is run up out of the way, leaving the curtain stretched freely between the tables U and 90 V. The frame 6 is then placed on the curtain, as seen at Fig. 5, thus holding the curtain in contact with the surface of the main table A, and the belts having changed from the right to the left pulleys through the 95 action of the tappets the screw-shafts P and P' are reversed, thus causing the narrow tables U and V to move toward each other and pass over the main table A; thereby drawing the sides of the curtain over the surfaces of the 100 narrow tables U and V onto the open frame G, as seen at Fig. 6. The curtain is thus en-

tirely laid on the frame 6, and the latter can then be removed and the curtain be allowed to dry in the folded position.

Having now described my invention, what 5 I claim as new, and desire to secure by Letters Patent, is—

1. The combination in a machine for folding curtains, of a balanced carrier having pins on its under side to engage the curtain at its 10 center, a rod adjacent to the carrier for supporting the curtain at about its center, two narrow tables below and lengthwise at each side of the rod, a fixed main table and means for moving the narrow tables toward and from 15 each other above the fixed main table, substantially as set forth.

2. The combination in a machine for folding curtains, with a fixed table, of two narrow tables above the fixed table, screw-shafts 20 operatively connected to said narrow tables

for moving the same toward and away from each other and above the fixed table, belts and driving-pulleys, a belt-shifter and tappets engaged by the narrow moving tables for operating the belts and reversing the mechanism, 25 substantially as set forth.

3. The combination in a machine for folding curtains, with a fixed table and two narrow tables above the fixed table and means 30 for moving the narrow tables toward and from each other, of a carrier and pins on its under side, hooks at its ends and a rod carried by said hooks for supporting the curtain, and weights for balancing the carrier, substantially as set forth.

JAMES HESELWOOD.
